UNITED STATES PATENT OFFICE.

ENOCH OHNSTRAND, OF SYRACUSE, NEW YORK, ASSIGNOR TO U. S. STEEL FURNITURE COMPANY, OF SYRACUSE, NEW YORK, A CORPORATION OF NEW YORK.

METAL DESK OR TABLE.

1,232,961.

Specification of Letters Patent. Patented July 10, 1917.

Application filed October 10, 1910. Serial No. 586,393.

To all whom it may concern:

Be it known that ENOCH OHNSTRAND, a citizen of the United States, residing at Syracuse, in the county of Onondaga and 5 State of New York, has invented certain new and useful Improvements in Metal Desks or Tables, of which the following is a specification.

My invention relates to desks or tables 10 made of sheet metal, said desks being constructed therefrom with a top, drawers and legs, panels, etc., substantially the same in appearance as the desks and table heretofore made from wood.

One object of my invention is to join the various parts of the desk together with interlocking joints or other mechanical fastenings so that when the desk is assembled complete it is extremely rigid and stable, at 20 the same time dispensing with rivets, screws and other fastening devices separate from the pieces themselves.

Another object of my invention is to make hollow many of the parts which heretofore 25 have been made solid in the wood art, thus materially saving in the weight of the desk.

Another object of my invention is to construct the desk of parts that are made principally of sheet metal, which parts can be 30 cheaply produced by punch presses and bending presses, the parts being so made that they will readily go together to make a complete finished desk with small expense for hand labor.

Another object of my invention is to construct the desk so that it can be readily knocked down to a certain extent, making it possible thereby to pack it in a very much 35 smaller crate than would otherwise be necessary and leaving it also easily assembled by an unskilled or inexperienced person.

Another object of my invention is to construct the various parts of the desk so that 40 they may be readily assembled or disassembled without the use of tools.

These and other objects of my invention will be more fully set forth in the specification and pointed out in the claims at the end thereof.

50 In the accompanying drawings,

Figure 1 is a perspective view of the desk as it will appear when finished.

Fig. 2 is a front elevation of the desk,

with the top omitted, showing the drawers in position on one side of the desk and the 55 drawers omitted from the other side of the desk.

Fig. 3 is a section on the line 3^x—3^x of Fig. 2.

Fig. 4 is a section on the line 4^x—4^x of 60 Fig. 3.

Figs. 5, 6 and 7 are side elevation, plan view and end elevation respectively of the 65 guide or channel which supports one of the drawers.

Figs. 8 and 9 are detail views, front and side elevation respectively, of the plate, partly broken away, that forms one of the end panels of the desk.

Figs. 10 and 11 are detail perspective 70 views of legs Nos. 4 and 2 respectively.

Fig. 12 is a detail showing the two side sections of the desk placed end to end, with the cover and back plate placed opposite them in the packing crate.

Fig. 13 is a vertical transverse section 75 through the extended drawer of Fig. 1, showing a portion of the desk in front elevation.

Fig. 14 is an enlarged detail of the upper 80 right hand corner of Fig. 4.

Fig. 15 is a vertical transverse section on the line 15^x—15^x of Fig. 3.

Fig. 16 is a section on the line 16^x—16^x of 85 Fig. 15.

Fig. 17 is a section on the line 17^x—17^x of Fig. 15.

Fig. 18 is a section on the line 18^x—18^x of Fig. 15.

Figs. 19 and 20 are details of the plates 90 that are interlocked by the joint shown in Fig. 18.

Fig. 21 is a section on the line 21^x—21^x of Fig. 2.

In the accompanying drawings, like reference numerals refer to like parts.

In the present embodiment of the invention, the improvements are illustrated as applied to a sheet metal desk. This desk has six legs thereunder, two at the back and 100 four at the front, numbered 2, 3, 4, 5, 6 and 7 respectively. It has also a top covered with heavy linoleum 8, laid on a steel plate 9, the edges of which plate may be bent down and in, as shown at the top of Fig. 4 105 and Fig. 14. The edges of the linoleum top

are beveled and the sheet of linoleum is held in place by the angle irons 10, which are held in place by the bolts 11, between which on all four sides of the desk the sheet of linoleum is securely clamped. The upper edge of the angle iron 10 is turned in to the better engage with the linoleum and clamp it in place.

The legs are made out of sheet steel bent 10 to the form shown by the parts 2, 4 and 5 indicated in cross section in Fig. 3, for the purpose of connecting to the panels and the various other parts that enter into the structure of the desk. As shown in Fig. 3, the 15 plate from which the leg is formed is bent to a right angle along the line of the leg that will be exposed at the corners of the desk when the finished leg is assembled therein. It will also be apparent from an 20 inspection of Fig. 3 that two of the flat sides of the legs will be exposed in each case, while a portion of each of the other two sides will be more or less concealed by the parts of the desk with which it engages. 25 The edges of the plate are in the case of the leg 2 turned in at right angles to the exposed sides and are again bent in to the reentrant or channel form shown extending parallel to the exposed sides of the legs. One of 30 the sides of the legs 4 and 5 is bent in the same manner, reentrant, while the other side of each of these legs is bent in first at right angles to the exposed side, and then outwardly, parallel to the exposed side, forming 35 an angle instead of a channel. In each case the channel or angle described is formed on the edges of the legs, materially strengthening it so far as the stiffness is concerned, and providing a convenient place on the leg 40 in each case for attachment to the other portions of the desk.

It will be understood that the leg 3 will be the same as the leg 2, and that the legs 45 6 and 7 will be the same as the legs 4 and 5, except that the shape and relation of the parts will be symmetrically reversed from right to left, as the difference in their location in the structure of the desk requires.

The outline or cross section of the legs 50 shown in Fig. 3 in solid lines is such as will be used for that portion of the leg in each case that connects with or abuts against the body of the desk.

As will be seen in Fig. 1, the desk is provided with sanitary legs which are left bare for ten or more inches above the floor, and at that part the sides of the legs are bent to a complete square, preferably with a slight taper, with their outer edges abutting 60 against each other, forming a seam, which seam is closed by fusing the metal with the well known oxygen acetylene flame. Into the open end of the leg thus formed is forced 65 a metal plug formed of sheet metal, bent or pressed or drawn to the required shape, to

completely fill the opening and close it and present a round surface to the floor on which the desk may stand.

In Fig. 3 the bottom of the legs is shown in square outline by the full and dotted lines, 70 while the intermediate and upper portion of the legs is shown by the full lines in the case of each of the legs 2, 4 and 5.

As shown in Figs. 10 and 11, each of the legs is left with a shoulder 51, 51 on which 75 rests the bottom plate 52 of the section. As seen in Fig. 3, three corners of this bottom plate are carried on the shoulders of the respective legs. The intermediate portions of the plate rest on and are supported by angles 80 formed on the bottom edges of the plates 17, 19 and 22.

In the leg 2 the reentrant sides 12 and 13 are slotted at regular intervals as shown in Figs. 4 and 11. The side 13 is perforated 85 with the openings 14 and the side 12 is also perforated in like manner. Likewise the leg 4 has its side 15 perforated, such perforations appearing at 16 in Figs. 4 and 10 at regular intervals. The legs 2 and 4 are 90 connected by the end panel plate 17. This panel plate has struck up thereon the lugs 18 at intervals corresponding to the perforations in the sides 13 and 15 above mentioned, so that by placing the plate 17 with the lugs 95 thereon against the sides 13 and 15 of the legs 2 and 4 respectively, and by giving to it an edgewise movement, the panel securely locks itself to the legs. The side 12 of the leg 2 is perforated in like manner and the 100 rear panel plate 19 is provided with lugs 20 which engage therewith in the same manner as the lugs 18 engage with the perforations in the sides 13 and 15 of the legs 2 and 4. Likewise the leg 5 is perforated on its side 105 21 in the same manner, and the inner panel plate 22 has the lugs 23 formed thereon to engage therewith. In the leg 4 the side 24 is perforated at suitable intervals at 26 to receive the reduced ends 25 of the cross rails 110 26 which form the supports for the ends of the drawers 40, closing the opening between the consecutive drawers in the desk. These cross rails are bent to the form of a channel and may be rolled with a suitable molding 115 as shown in cross section in Fig. 4, and on each end the channel is cut away to leave the two reduced ends or two parallel lugs 25 of sufficient width to correspond with the recesses in the legs. These lugs 25 may be 120 passed through to the interior of the leg and all of the lugs 25 of all the cross rails projecting into the leg 4 may be locked or tied into engagement therewith by the rod 27 which is passed down through all of said 125 lugs. Shoulders are left on the cross rails 26 which positively engage with the side 24, so that between such shoulders and the rods the cross rails are held securely in position with reference to said legs. Similar 130

cross rails 26^a and 26^b are provided at the top as shown in Fig. 4 between which is supported the front end of a shelf 90 which can be drawn out and in. Each of these cross rails has reduced ends that pass through and into the legs 4 and 5 and are fastened therein by the pins 27^a. These cross rails also have shoulders that abut against the outside of the legs, the shoulders and reduced ends being substantially the same as those shown in Fig. 3 in connection with the cross rails 26. The rear end of the shelf 90 carries a block that is too large to pass through the opening between the channels 26^c and 26^b. The shelf is also supported on suitable guides or runways which hold it to its proper movement.

The outwardly turned side 28 of the leg 4 is cut away as at 29^a at suitable intervals to receive the ends of the supporting channels 29 with which the sides of the drawers engage and in which channels the drawers are free to move in and out. Each of the channels 29 has struck up from the back thereof the lug 30 which engages at one end with the side 24 of the leg 4, and at the other end with the angle iron 31. This angle iron 31 has an upturned edge 32 corresponding to the upturned edge 28 on the leg 4 and is recessed at suitable intervals to correspond therewith, so that the channels 29 engaging with said recesses are between them held horizontal. The angle 31 is fastened at the bottom to the angle 33 and at the top to the angle 34 in any suitable manner. The angle 33 in turn is fastened to the bottom plate 52 in any suitable manner, but preferably by rivets or screws.

In Fig. 18 I have illustrated the form of interlocking joint that I prefer to use for the purpose of connecting the upright angle 31 and the horizontal angles 34 at the top and 33 at the bottom. As shown in Fig. 19, the horizontal member has a lip 67 struck up therein, leaving an opening in the plate adjacent thereto and partially covered thereby. At the corresponding place in the vertical channel 31 a lip 68 is struck up, leaving a similar opening in the plate partially covered thereby. These lips 67 and 68 are somewhat elastic, so that by placing the plates adjacent to each other the lips may be sprung sufficiently so that each passes into engagement with the opening in the plate left by the striking up of the other lip, thus locking each of the plates in position with relation to the other plate.

In Fig. 18 I have shown the channel 31 and the angle 34 assembled and held together by a joint of this kind. A corresponding joint is used for fastening the angle 33 at the bottom of the desk with the vertical channels.

As shown in Fig. 3, the leg 5 is formed substantially the same as leg 4 except that

the position and relation of the parts is reversed from right to left.

The cross rails 26 have reduced ends engaging with the leg 5 similar to those which engage with the leg 4, and the cross rails 70 are fastened to leg 5 by the locking pin 27 as heretofore described. The channels 29 are also fastened to leg 5 in the same manner as are the corresponding channels fastened to the leg 4.

The drawers of the desk are formed in any suitable manner of sheet metal, the body of the drawer being formed of a single piece, the front and back ends being suitably closed in any desired manner. The top 80 edges of the drawer, as shown in Fig. 13, are rounded off and bent out, and to avoid interference therewith the angles 28 are suitably cut away as shown at 29^b.

Each of the drawers 40 of the desk is 85 provided with one or more channels 35 on each side thereof that engage with the channel or channels 29 and by which the drawers are supported in the desk.

The inside panel 22 is turned in, in its 90 rear end and fastened to the panel 19 in any suitable manner. The opposite side of the desk from that illustrated in Fig. 3 is substantially the same except that the position and relation of the parts is reversed in order to make it symmetrical. The top plate 9 of the desk is fastened to the body of the desk in the following manner.

Fastened to the top of the rear panel plate 19 at suitable intervals are brackets 45 projecting inwardly. Similar brackets can be fastened in or to the legs in the front of the desk or in any other convenient part of the desk. At corresponding places in the top 9 blisters 46 are formed in the well 105 known manner by swelling the metal by a press or other suitable machine tool. This blister 46 is of such size and shape as to have an opening between it and the surrounding metal of the plate to take in one 110 of the horizontal arms of the brackets 45. These openings in the blisters are all of uniform size as are the horizontal arms of the brackets. When all the rest of the desk has been assembled the top is attached thereto, 115 by placing on it in the appropriate openings the angles 45. The top is then placed on the desk. The sides of the desk adjacent the blisters 46 are appropriately perforated and the angles 45 have threaded openings 120 therein opposite said openings in the sides of the desk, so that screws may be passed into said angles from the outside, thus securely fastening the top of the desk in place. Or the top may be connected to the desk by 125 first mounting the angles 45 permanently on the desk, and the top may then be engaged therewith by a sliding movement, the top having first been placed on the desk a little to the left of its final position as shown in 130

Fig. 4. In such case all the angles 45 must point in the same direction, so that the edge-wise movement of the top will bring all the blisters into locking engagement with the 5 angles 45. The top may be disengaged from the desk by reversing the movement of it. After the top has been placed in position as above described it may be locked in such position by turning the button 54, which button 10 ton is provided near the edge of the top as shown in Fig. 4. If desired two or more of these buttons may be provided, one on each side of the desk.

The recesses in the top plate 9 above referred to as blisters, may be provided for in any other suitable manner. Separate strips of metal bent to the proper shape may be attached to the plate by riveting, the object being to fasten lugs or other similar 20 attachment to the plate with which the brackets may engage for the purpose of holding the top of the desk.

To prepare the desk for shipment, the top of the desk may be separated from the body 25 and the two sections may be detached from each other and from the rear panel, after which the two end sections may be placed end to end with the rear panel and the top of the desk placed alongside of them, in 30 which position they may be conveniently crated into a comparatively small crate, making the size and weight of the package correspondingly smaller for shipment.

In Figs. 15, 16 and 17 I have shown an 35 improved device for locking the drawers of the desk after they have been placed in position. On the end of each drawer in each section except the top drawer is placed a locking dog 55. This locking dog has a 40 beveled end as shown in Fig. 16, and at a point intermediate between the bevel and the rear end of the drawer it is provided with a recess 56. This locking dog 55 may be most conveniently formed by extending 45 the channel 35 on one side of the drawer beyond the end of the drawer and shaping it in the manner above described.

Fastened to the top of the desk in any 50 suitable manner is the bracket 57 on which at 58 is pivoted the lever 59. At its left hand end, as shown in Fig. 15, this lever 59 carries a stud 60 to which in turn is connected a spring 61. The lower end of this 55 spring connects to a stud 62 mounted on a sliding plate 63. This plate 63 has formed therein the slots 65, 65 which engage with the studs 64, 64 mounted on the vertical angle 31. This plate has cut therein the recesses or holes 66, one for each of the dogs 60 55. When the parts are in the position shown in Figs. 15 and 16, the plate 63 is in its lowest position and the drawers of the desk with their dogs 55 are free to move in and out, the dogs 55 moving freely through 65 the openings 66. When, however, the plate

63 is raised, the solid part of the plate 63 is drawn into the recesses 66, preventing the outward movement of the drawers. This plate 63 can be raised in the manner I am now about to describe.

The channel 35 on the opposite side of the top drawer is finished with a cam 67, which cam, as the drawer is pushed in, engages with the right hand end of the lever 59 and presses it down, causing the plate 63 to rise and lock the drawers below it. The top drawer may be locked in the desk by any suitable key and lock, so that the locking of the top drawer controls and holds locked all of the other drawers in the desk below it.

A spring 61 is provided between the plate 63 and the lever 59 to make it possible to insert any of the lower drawers of the desk after the top drawer has been locked in position. The cam faces on the dogs 55 at the rear of such drawers strikes against the lower edge of the opening 66 in the plate 63 and forces the plate 63 down until the cam face of the dog 55 clears the opening and the drawer passes into its proper position, after which the plate 63 is again free to rise, being drawn up by the spring 61 drawing the solid part of the plate 63 into the recess 66 and locking the drawer in position.

I will now describe how the desk is assembled after the various parts have been prepared in the manner above described.

The legs 4 and 5 will first be connected by 100 the cross rails 26, which cross rails will be locked in place by the pins 27. The leg 2 will then be connected to the leg 4 by means of the end panel 17, which is placed in its proper position with relation to the legs 2 and 4 and then pressed down so as to close the interlocking joints between them by pressing the lugs 18 into engagement with the openings 16 and 14. The other section 105 of the desk will be assembled in like manner and the two sections will be connected by the rear panel 19. The plate 52 can have assembled thereon the angle 33 by means of a suitable interlocking joint, as heretofore 110 described, and the plate 52 can then be placed in position. The frame consisting of the angles 33 and 34 and the upright angles 31, 31 can then be assembled by sliding their interlocking joints together at the corners and closing the joints by any suitable press. The frame can then be placed in the section of the desk and connected to the front legs by the channels 29, 29. After 115 being so placed in position the angle 33 can be fastened to the plate 52 by passing screws 120 up through the plate into the threaded openings in the channel provided therefor. The sections of the desk are fastened together at the front by the cross rail 80 which has reduced ends 81 that pass through suitable 125 130

openings in the top of the legs 5 and 6 and shoulders that bear against the outside of the legs. The reduced ends are locked to the legs by pins 82, 82 that are passed down through them similar to pin 27 that passes through the shoulders 25. The top of the desk can then be fastened in place in the manner above described. The plate 52 is made of thin sheet metal and is very flexible, which permits the rear end of it to be sprung up, when the rear panel 19 with its flange 53 must be inserted or removed. To facilitate the removal or insertion of this panel 19 the two sections of the desk may be placed slightly radial to each other which permits the more ready disengagement of the flange 53 from the plate 52 or the panel 22.

Having thus described my invention, what I claim as new and patentable is as follows:

1. In a sheet metal desk, the combination with a pair of tubular rear legs, of a rear panel interlocking with both legs and having an outwardly-turned flange along its upper edge and an inwardly-turned flange along its lower edge, two pairs of tubular front legs, outside panels each interlocking with one of the rear legs and with one of the front legs of each pair, said outside panels having inwardly-turned flanges along their lower edges and outwardly-turned flanges along their upper edges, inside panels interlocking at their front ends with the other members of the two pair of front legs, having flanges at their rear edges abutting the rear panel and inwardly-turned flanges along their lower edges, drawer strike bars connecting the members of each pair of front legs, bottom plates resting on the inwardly-turned flanges at the lower edges of the back panel, the outside panels and the inside panels, and a top resting upon the flanges along the upper edges of the back panel, the outside panels and the inside panels.

2. In furniture, the combination with a tubular leg formed from sheet metal with an inwardly turned flange provided with a plurality of openings, of a panel having lugs struck up from one face thereof, within the edges of said panel, the lugs extending parallel with the panel and the openings being of a size to permit the lugs to lie within the same without interlocking with the tubular leg and to interlock with the tubular leg by a movement of the panel in its plane, the face of the panel bearing about the lug against the flat surface on the flange during such interlocking.

3. In furniture, the combination with a hollow support having an inwardly-turned flange provided with openings, of a panel abutting said flange, and provided with lugs struck up from one face thereof within the edges of the panel to enter the openings in

the flange in order to interlock with the latter, the adjacent edge of the panel being provided with a laterally extending flange, the free edge of which abuts the inner wall of the hollow support.

4. In furniture, the combination with a hollow support having an inwardly-turned flange, of a panel abutting one face of said flange and having a flange at its adjacent edge turned to engage the free edge of the support-flange and the inner wall of the support, the face of the panel which abuts the flange having means interlocking with the abutting face of said flange when the panel is moved in its plane.

5. In furniture, the combination with a hollow leg formed from sheet metal into rectangular form, one corner of the leg being cut away to provide an opening, and the opposite sides of the opening being formed with inwardly-turned flanges at right angles to each other and parallel to two walls of the leg, of two panels arranged at right angles to each other and each abutting one of the flanges, the flanges being provided with openings and the panels each being provided with lugs struck up therefrom within its edges to pass through said openings and to interlock with the flanges when the panels are moved in their planes.

6. In furniture, the combination with a hollow leg formed from sheet metal into rectangular form, one corner of the leg being cut away to provide an opening, and the opposite sides of the opening being formed with inwardly-turned flanges at right angles to each other and parallel to two walls of the leg, of two panels arranged at right angles to each other and each interlocking with one of the flanges, the edges of the two panels being provided adjacent to the leg flanges with flanges engaging the free edges of the leg flanges and also engaging the inner faces of the walls of the leg.

7. In furniture, the combination with a hollow leg formed from sheet metal with a vertical recess, of a drawer guide having its forward end coöperating with the outer face of the leg and provided with a finger struck up from the metal thereof and projecting therefrom from a point in rear of the forward edge and parallel with the guide to coöperate with the inner face of the leg, the forward end of the tongue being in rear of the forward end of the guide.

8. In furniture, the combination with a hollow support having an inwardly-turned flange, of a panel abutting and interlocking with one face of said flange, and having a lateral flange at its edge turned to engage the free edge of the support flange, the free edge of the lateral flange engaging the inner wall of the support.

9. In furniture, a tubular leg provided with a vertical slot, one wall of which is

provided with recesses, of drawer supports having portions at their forward ends engaging in said recesses to prevent vertical movement of the drawer supports and provided with means for detachably engaging an interior face of said leg to hold the drawer supports to the leg.

10. In furniture, the combination with a side panel, of a front support made from sheet metal into tubular form with a vertical recess and having the side panel interlocked therewith on one side of the recess, and a drawer guide interlocking at its forward end with the front support on the other side of the recess.

11. A leg for furniture composed of a single sheet of metal, the edges of which are bent together in direct abutment in one part of said leg, and the edges of which are bent inwardly in said leg at right angles to each other in another part of the leg.

12. The combination in furniture of a leg composed of a single sheet of metal, the edges of which are bent together in direct abutment in one part of said leg, and the edges of which are bent inwardly in another part of said leg at right angles to each other, forming sides or bearing surfaces thereon parallel to the sides of the desk, perforations in said sides, panels fitting against said sides and having lugs formed thereon, said lugs passing through and interlocking with said slots.

13. The combination in furniture of a sheet metal leg having one of its edges bent inwardly with interlocking slots formed

therein, the other of its edges bent outwardly, recesses in said edge, guides supported in said recesses and having positive interlocking connection with said leg.

14. The combination, in a sheet metal desk, of two tubular legs each having a plurality of openings, of drawer strike bars connecting said legs and formed of sheet metal into U-shape in cross section having shoulders and reduced ends, the shoulders bearing against the legs and the reduced ends passing through the openings in the legs and being provided with perforations, and a rod in each leg passing through the perforations of a plurality of said strike bars.

15. The combination in furniture of upright angular supports having recesses therein, and channeled drawer guides connecting pairs of said angled supports and fitting into said recesses, each of said guides having lugs formed thereon, between which and said guides said angled supports are embraced.

16. In furniture, a tubular leg having a vertical recess, a panel interlocking with said leg on one side of the recess, and a drawer guide interlocking with said leg on the other side of the recess.

In testimony whereof I affix my signature in presence of two witnesses.

ENOCH OHNSTRAND.
